UNITED STATES PATENT OFFICE.

JOHN HUME BELL, OF EAST ORANGE, NEW JERSEY, ASSIGNOR TO WESTERN ELECTRIC COMPANY INCORPORATED, OF NEW YORK, N. Y., A CORPORATION OF NEW YORK.

TELEGRAPH SYSTEM.

1,286,917.

Specification of Letters Patent. Patented Dec. 10, 1918.

Application filed July 12, 1917. Serial No. 180,167.

To all whom it may concern:

Be it known that I, JOHN H. BELL, a citizen of the United States, residing at East Orange, in the county of Essex and State of New Jersey, have invented certain new and useful Improvements in Telegraph Systems, of which the following is a full, clear, concise, and exact description.

This invention relates to telegraph systems and more particularly to telegraph transmitting apparatus and systems wherein current changes, imparted over a single line conductor, may be readily recorded either in code or in printed form at a properly equipped receiving station.

The object of this invention is to provide a transmitter of the above class wherein the functions are reliably and efficiently performed all in a manner to render service of particular value in connection with cable or submarine telegraph working.

In accordance with this invention a plurality of current sources and current potential affecting means are controlled by relay means, distributor means and suitable transmitter switching means in a manner to establish so-called three-unit code combinations, formed of currents having different strengths and polarities, over a line conductor in a manner to effect a printed record on a suitable receiving equipment at a distant station.

In the system herein disclosed the selecting impulses are preferably formed by different combinations or permutations of currents of opposite polarities, currents having predetermined potentials or strengths, and currents comprising incremented potentials or strength values.

40 This invention is illustrated diagrammatically in the accompanying drawing in which only so much of a telegraph transmitter equipment is shown as will be necessary to a clear understanding of the features of 45 this invention.

Referring to the drawing, a source of grounded current, indicated by reference character 1, is adapted to be connected over initiating contacts 20, 22, 24, 26 and 28 to 50 operate impulse permutating relays 30, 40, 50, 60 and 70. A lock-release relay 90 controlled through contacts on a current distributor 80, in turn effects the releasing of all the impulse permutating relays. A contact arm 81 of the distributor 80 is adapt-

ed to be rotated by means (not shown) in a counter-clockwise direction to successively establish connection between segments on the distributor and a main line conductor 89. A positive grounded current source 2 and a 60 negatively grounded current source 3, resistance units 4 and 5, and the segments 83, 84 and 85 of the distributor 80 are interconnected to the contact members of the relays 30, 40, 50, 60 and 70 in such a manner that 65 impulses differing in polarity and current strength may be successively impressed on the line conductor 89 in various combinations of a three-impulse code arrangement.

It will be understood that the arrangement and manner in which the initiating contacts 20, 22, 24, 26 and 28 are shown is merely for the sake of clearness in the drawing, and that these contacts may, and preferably are, arranged in a manner to be controlled and operated by a perforated message tape or strip all in a manner well known and practised in the art to which this invention pertains. And further, since arrangements for operating the current distributor 80 and an associated and coördinated feed for a perforated transmitting tape are well known in the art, it is not considered necessary to describe such a mechanism or driving arrangement herein. Therefore, only such parts of the distributor and transmitter as pertain more particularly to the features of this invention, are shown in the drawing.

In more specifically describing the features of this invention a number of selecting code cycles will be assumed and traced through the various steps by which they may be initiated and imparted to the main line conductor 89. Let it first be assumed that 95 it is desired to send out a regular cycle of three impulses predeterminedly adapted to select the letter O at a properly equipped receiving station (not shown), and let it be further assumed that such cycle shall comprise a positive impulse of incremented predetermined voltage, followed by a negative impulse, also of incremented predetermined voltage, and a third impulse consisting of a negative current of predetermined voltage. Since the travel of the contact arm 81 of the current distributor 80 is adapted to be controlled in unison with the forward movement of a perforated transmitting strip (such mechanism and strip not 110

shown), contacts 20, 22, 24, 26 and 28 are closed either in advance of or on the instant the contactor arm 81 reaches respective ones of the segments 83; 84 and 85. The action for the present example results, first, in current from the grounded source 1 traversing contacts 20, conductor 21, winding of relay 30, conductors 31 and 18, contacts 91 of relay 90 to the earth connection 92. The resulting operation of the relay 30 closes through its contacts 33 and a conductor 15 a self-locking circuit in parallel with the initiating contacts 20, and through the contacts 32 of this relay a path is established which may be traced from the positive side of the grounded current source 3, conductors 10 and 36, contacts 32 of the relay 30, conductor 38, contacts 57 of a relay 50, conductor 54 to the segment 83 of the distributor 80. When the contactor arm 81 comes over the segment 83, connection is established from this segment by the spanning wiper 82 of the arm 81 to the contactor ring 79 to which the line conductor 89 is connected. Accordingly, during the time the contactor arm 81 is passing over the segment 83, positive current at the full potential (incremented strength) of the source 3 is impressed on the main line conductor 89, over the circuit just traced. The second action set up by the perforated transmitting tape results in the simultaneous momentary closing of contacts 22 and 26, thereby establishing a connection from the current source 1, bus 16, contacts 22, conductor 23, winding of the relay 40, conductors 41 and 18, contacts 91 of the relay 90 to the earth connection 92. Relay 40 operates by this current to establish a self-locking circuit through its contacts 43 and the conductor 15, and through the closing of its contacts 44, prepares an impulse path which will presently be traced. In phase with the operation of relay 40, current from the source 1 through bus 16 traverses the contacts 26, conductor 27, winding of the relay 60, conductors 61 and 18, contacts 91 of the clearing-out relay 90 to the earth connection 92. The relay 60 thereupon operates to form a self-locking circuit through its contacts 63 and the conductor 15, and through the contacts 65 of this relay, acting in conjunction with the contacts 44 of the relay 40 to complete an impulse circuit which may be traced from the negative side of the grounded current source 2, by way of conductors 8 and 46, contacts 44 of the relay 40, conductor 48, contacts 65 of the relay 60, and conductor 62 to the segment 84 of the distributor 80. Accordingly, during the time the contactor arm 81 is passing over this segment 84, negative current at the full potential (incremented strength) of the source 2 is imparted to the main line conductor 89. In setting up the third and last unit of this three-impulse code the perforated strip

closes the contacts 28, thereby completing a circuit from the bus conductor 16 of the current source 1, conductor 29, winding of the relay 70, conductors 71 and 18, contacts 91 of the lock-release relay 90 to the earth connection 92. In response to this current the relay 70 acts and establishes a self-locking circuit from the current bus conductor 15 over its contacts 73. Through the contacts 75 of this relay is now completed an impulse path, which may be traced from the negative side of the current source 2, resistance unit 4, conductor 11, contacts 75 of the relay 70, conductor 76, to the segment 85 of the distributor 80. Therefore, during the interval 75 the contactor arm 81 of the distributor 80 is passing over the segment 85, negative current at a predetermined potential lower than the potential of the source 2, due to the presence of the resistance 4, is established with 80 the line conductor 89. At a proper instant after the contacting arm 81 has passed from the segment 85 an independent brush 87, carried by this arm, but insulated therefrom, passes over and spans the gap space between 85 two contact segments 86 and 88, thereby completing a circuit from the current source 1, bus conductor 16, the segment 86, brush 87, segment 88, conductor 93, the winding of the lock-release relay 90 to the earth connection 92. This results in the operation of the relay 90, and the separation of its contacts 91 disconnects the bus conductor 18, thereby deenergizing the relays 30, 40, 60 and 70, permitting them to restore to their 100 normal condition.

After the contactor arm 81 of the distributor 80, in its regular travel, has passed the lock-release contact segments 86 and 88, the relay 90 is released and while the arm 81 is traversing the three uppermost or idle segments, the perforated message tape may continue its travel and perform the selecting of impulse control relays for setting up on the segments 83, 84 and 85 a combination impulse cycle for the next character to be transmitted.

As shown in the drawing, through interconnection of the contact members of different ones of the relays 30, 40, 50, 60 and 70, circuit paths are normally established between the current sources 2 and 3 and each one of the segments 83, 84 and 85 of the distributor 80. In the setting up of a three-unit code selecting cycle it will therefore be 115 understood that the currents normally common to the three segments may be employed as a character selecting cycle, or such normal current condition of any one of the segments may be employed in combination with any 120 other current unit condition which may be set up by the impulse-character control relays. Therefore, a selecting cycle will now be described in which the currents normally 125 present at the segments 83, 84 and 85 of the 130

distributer 80 will be considered. For convenience, let it be assumed that the transmitting of a code cycle for the character A is desired, and that three impulses of positive current, each having the same predetermined potential or current strength, will be required. To accomplish this, no holes corresponding with the initiating contacts 20, 22, 24, 26 and 28 will be present in that portion of the transmitting tape which corresponds with the letter A. The relays 30, 40, 50, 60 and 70, therefore, remain inert while the trailer or contactor arm 82 of the distributer 80 makes a revolution. On arriving at the segment 83 the contactor arm 81 establishes a circuit which may be traced from the positive side of the current source 3, the resistance unit 5, conductors 13 and 39, normal contacts 35 of the relay 30, conductor 38, normal contacts 57 of the relay 50, conductor 54, the segment 83 of the distributer 80, thence over the brush or wiper 82 of the trailer arm 81, to the contactor ring 79, to which the main line conductor 89 is connected. For the segment 84 the normal circuit may be traced from the positive side of the current source 3, resistance unit 5, conductors 13 and 49, normal contacts 45 of the relay 40, conductor 56, the normal contacts 67 of the relay 60, conductor 62 to the segment 84, and upon the trailer arm 81 reaching this segment, connection is established therefrom to the main line conductor 89 as described. The last current impulse unit of this impulse cycle may be traced from the positive side of the current source 3, resistance unit 5, conductor 13, the normal contacts 77 of the relay 70, conductor 76, to the segment 85. In turn the trailer arm 81, in passing over the segment 85, establishes a connection therefrom to the line conductor 89, thereby completing a three-unit impulse cycle consisting of like poled impulses of current of predetermined strength by which the character A may be selected on a suitable receiving arrangement at a distant station (not shown).

From the drawing and the foregoing description it will be apparent that during the time the relays 50, 60 and 70 are inert complete connections from the positively poled current source 3, as reduced in potential by the presence of the resistance unit 5, are established to the segments of the distributer 80, and that when these relays are in the operated position the segments 83, 84 and 85 are disconnected from the positive source 3 and switched to the negatively poled source 9 from which the potential of the current supplied is correspondingly reduced by the presence of the resistance unit 4, connected in series with the common or bus conductor 11. And further, that the relays 30 and 40 control the disconnecting of the resistance units 4 and 5 and the connecting of the cur-

rent sources 2 and 3 at their full potentials to the contact members of the pole changing relays 50 and 60. Accordingly, the relays 50, 60 and 70 may be considered as polarity reversing relays, while the relays 30 and 40 70 may be considered as controlling the matter of the potentials or the incrementing of voltages for the signaling impulses supplied through the distributer 80 to the line conductor 89.

For multiplex working, the three idle segments shown on the distributer 80, may be connected to a second transmitting equipment similar to that shown in the drawing, or a receiving system suitable for reproducing or recording telegraphic signals from a transmitter located at a distant station may be connected to be operated from these segments, it being understood that a distributer and other equipment similar to that shown in the drawing would be provided at such distant station.

What is claimed is:

1. In a telegraph system, a line circuit, a plurality of current sources, a plurality of relays, means for selectively operating said relays, means for retaining said relays operated, means controlled by said relays for preparing various potentials and polarities from said current sources in advance of use, and distributer means for establishing said prepared currents with the line circuit.

2. In a telegraph system, a line circuit, a plurality of current sources, resistances for providing a plurality of potentials available from said current sources, relays for selecting predetermined ones of said plurality of potentials, relays for selecting predetermined polarities from said selected potentials, and distributer means for establishing predetermined periods of current action by said selected potentials and polarities in said line conductor.

3. In a telegraph system, a line conductor, a plurality of current sources, resistances for providing different potentials available from said current sources, relays for selecting predetermined different ones of said potentials, relays for selecting predetermined polarities from said selected potentials, distributer means for including said selected polarities with said line conductor, and a relay for disabling said first and second mentioned relays.

4. In a telegraph system, a line conductor, a plurality of current sources, resistances for providing different potentials available from said current sources, a plurality of relays for selecting predetermined potentials and polarities from said sources of current, contacts controlled by said plurality of relays for continuing a selected condition of said relays, and distributer means for including said selected potentials with said line conductor.

- 4
5. In a telegraph system, a plurality of relays, means for selectively controlling said relays, a plurality of current sources, distributor means and a line circuit controlled thereby, a plurality of circuits formed serially through contacts of different ones of said relays for joining said sources of current with said distributor means, and resistances included in certain ones of said series 10 circuits.
  6. In a telegraph system, a plurality of relays, a plurality of contacts for selectively controlling said relays, contacts controlled by said relays substitutable for said con-

trolling contacts to complete respective locking circuits for said relays, a plurality of current sources, a plurality of circuits extending from said sources of current respectively through pluralities of contacts of said relays, resistance units included in certain ones of said plurality of circuits, a line circuit, distributor means for successively joining said plurality of circuits with said line, and means controlled by said distributor for disabling said relays. 15

In witness whereof, I hereunto subscribe my name this 10th day of July A. D., 1917.

JOHN HUME BELL. 25
